(57) **CLAIM**

The ornamental design for a card connector, as shown and described.

DESCRIPTION

FIG. 1 is a top plan view;

FIG. 2 is a front elevation;

FIG. 3 is a rear elevation;

FIG. 4 is a left-side elevation;

FIG. 5 is a bottom plan view; and,

FIG. 6 is a perspective view, wherein the right-side elevation is symmetrical with the left-side one is not included herein.

The present design is characterized in that a frame of the card connector for use with any one or two of a plurality of memory cards is of a two- or more-storied structure, such that each story has no bottom plate but comprise a simple array of pin contacts that are fixed in and along its back wall, and that its card receiving and unloading mechanism is disposed in its side walls adjacent to its front opening.
